UNITED STATES PATENT OFFICE.

JOHN M. DALY, OF CHICAGO, ILLINOIS.

COMPUTING-MACHINE.

939,479.

Specification of Letters Patent. Patented Nov. 9, 1909.

Application filed April 10, 1907. Serial No. 367,449.

To all whom it may concern:

Be it known that I, JOHN M. DALY, a citizen of the United States, residing at Chicago, in the county of Cook and State of Illinois, have invented certain new and useful Improvements in Computing-Machines; and I do hereby declare that the following is a full, clear, and exact description of the invention, which will enable others skilled in the art to which it appertains to make and use the same.

This invention has reference to a computing machine and relates particularly to a device for equating train tonnage or for 15 measuring the resistance of railway trains, although the invention herein may be used with equally as good results on other and various computing machines.

One of the objects of the present invention is combining a stationary stop member and an interchangeable scale with a registering device.

A further object of this invention is to make possible a computation upon any basis 25 desirable, each change of scale representing a different basis or rate for calculation.

The results to be obtained by the present invention are similar to those found in earlier applications for patent filed by me on 30 Jan. 4th, 1906, bearing Serial No. 294,662 and Jan. 30th, 1907, bearing Serial No. 354,908.

For a further and full description of the invention herein and the merits thereof, and 35 also to acquire a knowledge of the details of construction of the means for effecting the result, reference is had to the following description and drawings hereto attached.

While the essential and characteristic features of the invention are susceptible of modification, still the preferred embodiment of the invention is illustrated in the accompanying drawings, in which:—

Figure 1 is a top plan view of my improved computing machine with top of casing removed and parts thereof showing the arrangements of the working parts of device in said casing; Fig. 2 is a top plan view of casing alone, with scale removed; Fig. 3 is 45 a top plan view of a computing machine, embodying my improvements, showing a scale to be used with a 1040 ton rated engine, placed in position and one car of eighty gross tons registered upon the machine; Fig. 50 4 is a view similar to Fig. 3 with the excep-

tion that the registering mechanism has been operated to register a car of 30 gross tons; Fig. 5 is a view similar to Fig. 3 with the exception that scale based on different rating is used; Fig. 6 is a view similar to Fig. 4 60 with exception that the scale is based upon different rating and similar to scale in Fig. 5; Fig. 7 is a transverse cross-section through the casing, taken on the line *y*—*y* of Fig. 2; Fig. 8 is an annular scale adapted to be 65 manually inserted in the casing, showing respectively its face, and end view and sectional view along the line *x*—*x*.

Like numerals of reference indicate corresponding parts throughout the figures. 70

In my pending application, bearing Serial Number 354,908 I have explained fully the operation of the registering wheels disclosed in this application and therefore they need only be briefly referred to here, as they form 75 no part of the present invention, except as it may be employed with some suitable registering mechanism, and that disclosed to a certain extent, is the preferred arrangement. The wheels 14, 15, 16 and 17 are mounted to 80 having a co-operative relation, being successively actuated through the operation of the circular plate or disk 9, on the lower surface 8 of which, are arranged teeth meshing with a pinion 12, which, with each operation imparts a like movement to the wheel 14; both 85 the gearing of the plate 9 and the pinion 12 are shown in dotted lines in Fig. 1. A suitable means may be employed to revolve this circular plate, in this instance, I have arranged a series of small holes 11 near the periphery, in which a pin may be inserted 90 and the disk manually turned. With each turn of the plate this pin which reaches far enough below the surface of the plate to 95 engage the lever 40 pulls this and its corresponding lever 38 into dotted position seen in Fig. 1, which by means of connecting rod 37 and lever 36 turns the sleeve 32; the lever 33 lifting ratchet 34 which in turn revolves car 100 numbering wheels 29 operating wheel 30 at predetermined intervals as has been explained.

I think it unnecessary to detail to any great extent the mechanism operated by the disk 9 to impart motion to the registering and numbering wheels, nor to the instrumentalities which, by reversing the disk 7, the numbers upon all the wheels are turned to naught. The brief description I have 110

given along with the references made, I believe to be all that is sufficient to make the said device understood.

The pinion 12 is preferably composed of ten teeth, a number corresponding to the number of figures on registering wheels; and the arcs subtended by chords drawn from center to center of contiguous pin holes 11 are equal to those cut by the pitch of the gear teeth 8 on under side of disk 9; thus during the revolution of the circular plate the registering wheels will register an amount, more than that already registered, equal to the number of holes which pass a given point on the periphery; in other words, with the motion of the disk 9 equal to the circumferential distance between contiguous holes 11 the registering wheel 14 will have turned a distance equal to that occupied by the figure upon the curved face of the registering wheel.

An engine has a specified tractive power dependent upon size of boiler, cylinders, weight, etc., and each car requires a certain amount of force to overcome its inertia or rest. Each railroad has certain grades and curves to be overcome, so that an engine of a certain draw bar pull on one line has more work to haul a certain number of cars between two points than the same would have on another, owing to the differences in the curves and grades of the two tracks. An engine will, therefore, be more effective on a straight track, the difference in the work required to do in each case being allowed for by the proper graduation of the scales; the scales being based preferably upon dynamometer car tests over certain roads for certain engines.

In my former application, bearing Serial No. 354,908, I have had a fixed scale and a movable stop, the stop adaptable to any engine on any road; but in the present invention I have arranged a series of differently graded interchangeable scales in combination with a fixed stop to take the place of the former. For the sake of explanation I have shown two of such scales, one in Figs. 3, 4 and 7 and the other in Figs. 5 and 6, illustrating engines with respectively 1040 and 2500 ton pulling capacity over certain lines.

The scales may be made of any suitable material and of any size or shape, but for the purpose of explanation I prefer to show them as rings 1, upon which may be embedded, embossed or suitably attached, numbers or characters by which cars of various gross weights may be shown. I have, for convenience, shown numerals, each number representing in tons, a car of like gross weight. There is a dissimilarity in my arrangement of these characters to suit the different pulling capacities founded as I have said before upon dynamometer cars.

For the purpose of accurate reading, I have placed them opposite small spacing lines which coincide with perforations 11, as is shown in my drawings, upon proper adjustment of the scale rings; the spaces between each line being proportionately equal to the spaces between perforations. The casing 6 is formed so that the scales may lie therein and suitable clamps 5 in combination with lugs 3 or other means may be furnished to prevent the said scale rings from being moved from the proper adjustment or position. An appropriate stop 7 is also provided made in any way for adaptation to its particular use.

I have in my drawings shown clamps 5 pivotally connected to the casing 6 which may be swung backward and forward to admit and clamp scale rings into position. The shelf 2, cut away in one portion to allow the lever 40 to swing, is furnished as a resting place for the scale rings. The lugs 3 which I have shown, fit into indentures 4 in scale rings; this being one method of preventing the scale rings 1 from revolving. The stop 7 I have illustrated, is merely a small metal bar pivotally fastened to casing 5 at point 12; it may be swung as shown in dotted lines in Figs. 3 and 5 to admit the scale ring to casing; but prevented from swinging too far in either direction by small lugs 10 on surface of casing.

Now, upon making up a freight train in which this device may be used, the number of the engine is first ascertained and its corresponding scale ring over that particular road is placed in position. Then for each car to be transported, its gross weight is learned and the propelling pin is placed in the hole 11 opposite a number designating an amount equal to the gross weight of the car. The pin and disk are turned clockwise until the propelling pin strikes against the fixed stop 7 and the number of gross tons that car represents on that road will be registered upon the registering wheels. A car at a time may be added and the same process employed so long as neither the limit in the number of cars has been reached, nor the sum upon the registering mechanism exceeds the tonnage rate of the engine.

For the purpose of illustrating the difference there would be in scales for engines over certain roads I show the Figs. 3 and 4 to be used with a 1040 ton rated engine, Figs. 5 and 6 with a 2500 ton rated engine. For convenience, I have taken 80 tons as a unit, upon which the computation is based, which therefore accounts for the registration of 80 upon the machine with both scales in Figs. 3 and 5; the arrows indicating the path of the propelling pin. In Figs. 4 and 6, the difference is evident, in each case a car of 30 gross tons has been registered and their respective tonnage added upon the machine.

This cause for the difference in the scales may be better understood when explained that an engine of a large draw bar pull can pull more cars than an engine of smaller pulling capacity, consequently, each car of a long train owing to friction, curves, etc., will weigh proportionately more than one in a shorter train, hence, the obvious difference.

Having thus fully described my invention, 10 what I claim and desire to secure by Letters Patent of the United States, is:—

1. In a computing machine, the combination of a plurality of coöperating registering wheels, a rotatable member operatively connected to said wheels, and a plurality of interchangeable rings adapted to encircle said member, each ring provided with a different scale to coöperate with said member and register wheels.

2. In a machine for equating train tonnage, the combination of suitable registering mechanism, and a plurality of interchangeable members, each member having a scale attached thereto, the said scales being dissimilar for the purpose of suiting the several scales to engines of different pulling capacity.

3. In a machine for equating train tonnage, the combination of registering mechanism, means for operating said mechanism, and a plurality of interchangeable rings, adapted to encircle said register operating means, and each ring having a scale based upon a different rate for calculation.

4. In a machine for equating train tonnage, the combination of registering mechanism, a revoluble disk operatively connected with said mechanism, a plurality of interchangeable members adapted to have association with said disk and having a scale attached thereto, and serving as a guide to the operation of said disk, said scales being dissimilar for the purpose of suiting the several scales to engines of different pulling capacity.

5. In a computing machine, the combination of a plurality of registering wheels, a plurality of tallying wheels, a disk operatively connected with the registering wheels, means capable of being operated simultaneous with the operation of the disk, for actuating the tallying wheels, and a plurality of interchangeable rings adapted to encircle said disk, each of said rings having a scale attached thereto based upon a different rating for calculation.

6. In a computing machine, the combination of registering mechanism, a disk operatively connected with said mechanism, said disk provided with an annular row of perforations arranged for the insertion of means at various points on said disk to rotate the same, and a plurality of interchangeable rings, each of said rings provided with a scale composed of characters, said characters

placed opposite spacing lines which coincide with the perforations in the disk, the spaces between each line being proportionately equal to the spaces between said perforations.

7. In a computing machine, registering mechanism, actuating means therefor, and interchangeable rings each having a scale attached thereto, and a member for limiting the movement of said actuating means.

8. In a computing machine, registering mechanism, actuating means therefor, interchangeable annular rings each having a scale to coöperate with said actuating means, and a member for limiting the movement of said actuating means.

9. In a computing machine, registering mechanism, actuating means therefor, interchangeable rings each having a scale attached thereto, each of said scales based upon a different rate for calculation, and a member for limiting the movement of said actuating means.

10. In a computing machine, registering mechanism, actuating means, detachable annular rings each having a scale attached thereto, said scales based upon a different rate for calculation, and a member for limiting the movement of the actuating means.

11. In a computing machine, registering mechanism, rotatably supported means to be manually operated for actuating said registering mechanism, and interchangeable members, each having a scale attached thereto, adapted to encircle said actuating means and based upon a different rate for calculation.

12. In a computing machine, registering mechanism, rotatably supported means to be manually operated for actuating said registering mechanism, interchangeable rings adapted to encircle said actuating means, and having scales attached thereto, each of which are based upon a different rate for calculation.

13. In a computing machine, registering mechanism, rotatably supported means to be manually operated for actuating said registering mechanism, interchangeable members, each having a scale adapted to encircle said actuating means and based upon a different rate for calculation, and means for governing the movement of said actuating means.

14. In a computing machine, registering mechanism, rotatably supported means to be manually operated for actuating said registering mechanism, interchangeable rings adapted to encircle said actuating means, and having scales attached thereto, each of which are based upon a different rate for calculation, and means overlying the path of movement of said rotatably supported means for limiting the movement thereof.

15. In a computing machine, registering mechanism, a disk geared to such mechanism and adapted to be manually actuated, and interchangeable rings having scales

adapted to encircle said disk, each of which are based upon a different rate for calculation.

16. In a computing machine, registering mechanism, a disk geared to such mechanism, and adapted to be manually actuated, a removable member having a scale coöperating with said disk and registering mechanism, and a stop member for limiting the movement of said disk and pivotally supported to allow for the removing of said member.

17. In a computing machine, registering mechanism, a disk geared to such mechanism, and adapted to be manually actuated, a removable ring encircling said disk; a scale on said ring adapted to coöperate with said disk and registering mechanism, and a stop member normally overlying a portion of said ring and disk for limiting the movement of the disk, and pivotally supported to be swung out of the way of said ring to adapt the same to be removed.

18. In a computing machine, the combination with the registering mechanism and the actuating means therefor, of a removably supported ring, a scale attached to said ring, and a stop member normally overlying a portion of said ring and pivotally supported to be swung across the face of the ring.

19. In a computing machine, the combination of a casing having an annular seating portion, a series of interchangeable rings adapted to be detachably secured on the seating portion of said casing, and scales attached to said rings, each of which are based on a different rate for calculation.

20. In a computing machine, the combination of a casing registering mechanism

40 mounted therein, a revolvably mounted disk geared to said registering mechanism and provided with a series of perforations arranged annularly on said disk into which may be inserted means for manually actuating the disk, interchangeable rings adapted to be detachably connected with said casing, and scales adapted to be attached to said rings, each of which are based on a different rate for calculation.

45 21. In a computing machine, the combination of a casing, registering mechanism mounted therein, a revolvably mounted disk geared to said registering mechanism, and provided with a series of perforations mounted on said disk into which may be inserted means for manually actuating the disk, interchangeable scales coöperating with said disk and registering mechanism, and means attached to said casing for limiting the movement of the disk.

50 22. In a computing machine, registering mechanism, interchangeable rings, having scales attached thereto and coöperating with said mechanism, and means for preventing movement of said rings.

55 23. In a computing machine, registering mechanism, interchangeable rings, scales attached thereto and coöperating with said mechanism, and lugs in combination with indentures coöperating to prevent movement 70 of said rings.

In testimony whereof I affix my signature, in presence of two witnesses.

JOHN M. DALY.
